UNITED STATES PATENT OFFICE.

BUBIN MILLARD SWEARENGIN, OF BIRMINGHAM, ALABAMA.

CARBURETOR.

Application filed August 19, 1925. Serial No. 51182

My invention relates to a new and improved type of carburetor in which a regulable volume of air is carbureted by causing it to flow over a body of gasoline or like fuel, in combination with adjustable means to regulate the clearance above the gasoline level for the flow of air, thereby controlling the extent of the enrichment of the carbureted air.

10 My invention contemplates the employment of a carburetor containing a substantial body of gasoline or other volatile fuel which is maintained substantially at a constant level, there being an air intake at one end 15 and a mixture discharge at the other with an interposed baffle, preferably of corrugated type, under which the air is forced to flow in traversing the tank and which is pivoted so that its free end can be adjusted relatively 20 to the gasoline level, thereby controlling the carbureting action of the carburetor.

its other end connected by links 10, 11 and 12 to the free end of a corrugated air baffle 13, mounted within the tank 14 which constitutes the carbureting chamber. This tank is preferably elongated and has at one end a spaced transverse chamber 15 into the center of which the air pipe 4 enters. A corresponding transverse chamber 16 at the other end of the tank has an intermediate horizontal baffle 17 interposed between the top air inlet holes 18 and air inlet holes 19 in a lower baffle plate 20. Below the air ports 19 I arrange several baffles 21, attached to the end wall 22 of the tank which is preferably deeper than the other end wall 23, so that the bottom 24 of the tank pitches downwardly towards the end wall 22. I arrange transversely across the bottom of the tank a series of baffles 25 having bottom notches or ports 26 to permit the gasoline or other volatile fuel therein to seek a common level in

My invention further contemplates co-ordinating the adjustment of the air baffle in the carburetor with the air intake or butterfly valve in the air connection to the intake manifold, thereby effecting an automatic control of the mixture.

25

the tank. I provide a supply chamber 27 for the gasoline mounted on the wall 22 and having ports 28 near its bottom through which the fuel will flow into the tank 14. A float 29 in the tank 27 controls an inlet needle valve 30 which admits the liquid fuel

30

My invention further comprises novel details in the construction of the carburetor tank, all of which will be more clearly understood by reference to the following specification and to the accompanying drawings, in which:—

Fig. 1 is a perspective view partly broken away illustrating my improved carburetor.

Fig. 2 is a longitudinal sectional view on the line 2-2 of Fig. 1.

Fig. 3 is a transverse cross-sectional view on the line 3-3 of Fig. 2.

40 Similar reference numerals refer to similar parts throughout the drawings.

In the embodiment of my invention illustrated in the drawings, I show conventional

ally an intake manifold 1 having a supply line 2 leading thereto and containing a check valve 3. This supply line 2 leads from a pipe 4 having air inlet ports 5 at its upper end and between said ports and the connection for the line 2 is interposed a butterfly valve 6. A guard 7 is rigidly mounted in spaced relation above the air ports 5 and a bell crank 8 is fast on the butterfly valve stem and has one end connected to a control rod 9 leading from the dash or from 55 any gas control element of the car and has

its other end connected by links 10, 11 and 12 to the free end of a corrugated air baffle 13, mounted within the tank 14 which constitutes the carbureting chamber. This tank is preferably elongated and has at one end a spaced transverse chamber 15 into the center of which the air pipe 4 enters. A corresponding transverse chamber 16 at the other end of the tank has an intermediate horizontal baffle 17 interposed between the top air inlet holes 18 and air inlet holes 19 in a lower baffle plate 20. Below the air ports 19 I arrange several baffles 21, attached to the end wall 22 of the tank which is preferably deeper than the other end wall 23, so that the bottom 24 of the tank pitches downwardly towards the end wall 22. I arrange transversely across the bottom of the tank a series of baffles 25 having bottom notches or ports 26 to permit the gasoline or other volatile fuel therein to seek a common level in the tank. I provide a supply chamber 27 for the gasoline mounted on the wall 22 and having ports 28 near its bottom through which the fuel will flow into the tank 14. A float 29 in the tank 27 controls an inlet needle valve 30 which admits the liquid fuel from a supply pipe 31 and acts to maintain a substantially constant level in the tank 14. The chamber 27 has a removable cover 32 by means of which access may be had to the valve mechanism. The corrugated baffle 13 is pivotally mounted on a cross rod 33 which is set so closely against the top wall of the tank that substantially all of the entering air is forced to travel under the baffle to reach the outlet chamber 15, since the sides of the baffle engage slidably the sides of the tank. The tank has a priming cap 34 and a drain cock 35.

The operation of the device is as follows. Having filled the tank with liquid fuel, the control rod 9 is moved to set the parts in the position shown in Fig. 2 so that the entering air is forced, throughout the major portion of its travel, into intimate contact with the fuel and is thus delivered as a rich mixture to the intake manifold, which is desirable on starting. As the motor speeds up, the bell crank is shifted by the control rod 9 so as to lift the baffle, thus thinning the mixture until, when fully raised, the thinnest mixture is obtained and the butterfly valve 6 is closed. The baffles 25 keep the fuel from splashing too much and the float valve 100

maintains its constant level. If desired, a longitudinal baffle 36 may be employed to reduce transverse splashing in the tank.

Though I have described with great particularity the details of the embodiment of the invention herein shown, it is not to be construed that I am limited thereto, as changes in arrangement and substitution of equivalents may be made by those skilled in the art without departing from the invention as defined in the appended claims.

Having thus described my invention, what I claim as new and desire to secure by Letters Patent, is:—

15. 1. In a carburetor, a liquid fuel tank having spaced air inlet and outlet ports, a movable baffle interposed between said ports and disposed to overlie the fuel at an acute angle so as to force the air in traversing the tank 20 to flow between the opposed surfaces of the baffle and the fuel, and a remote control means to move the baffle and regulate the air passage from beneath the baffle to vary the richness of the carbureted mixture.
20. 2. A carburetor comprising a chamber having means to maintain liquid fuel therein at a substantially constant level, means to admit air and to discharge a carbureted mixture from said chamber, a baffle provided 30 in the chamber and so disposed as to cause the air to flow between the surface of the baffle and the surface of the liquid fuel and to pass outwardly from the chamber under one edge of said baffle, and control means 35 for the baffle to adjust said edge with respect to the liquid fuel surface.
30. 3. A carburetor comprising a chamber and means to maintain a substantially constant level of liquid fuel therein, means to admit air to the chamber, an outlet for the carbureted mixture, a hinged baffle adapted to cause the entering air to flow between it and the fuel in passing to said outlet, a pipe leading from said outlet to an engine manifold, an auxiliary air valve for admitting air to said pipe, and a common control for adjusting said valve and baffle to regulate the fuel mixture.
40. 4. A carburetor comprising an elongated tank having means to maintain liquid fuel at a substantially constant level therein, an air inlet near one end of the tank, a hinged baffle adapted to force the air entering said inlet to pass under it and in surface contact 45 with said fuel, an outlet for the carbureted mixture, a pipe for conducting said mixture to the intake manifold of an engine, a valve

for admitting air to said pipe, and means to jointly control said valve and baffle to close the air valve as the clearance between the baffle and fuel level is increased, and vice versa.

5. The combination with an air supply pipe for an intake manifold and an air valve for admitting air to said pipe, of a carburetor having communication with said pipe between the valve and manifold, said carburetor comprising an elongated chamber having means to maintain liquid fuel at a substantially constant level therein, breaker plates submerged in the liquid fuel, a hinged baffle in the tank, means to cause air flowing through the tank to pass between the fuel and said baffle, and an operating connection between the air valve and baffle for joint operation, substantially as described.

6. A carburetor comprising a tank and means to maintain liquid fuel at a substantially constant level therein, means to pass an air current through the tank over the fuel surface, and an adjustable elongated corrugated baffle coacting with the tank sides to define a passageway for the air current, said baffle being substantially coextensive in length with the tank and having its corrugations extending in the direction of flow of the air current thereunder.

7. A carburetor comprising a tank and means to maintain liquid fuel at a substantially constant level therein, means to pass an air current through the tank over the fuel, a baffle hinged to the tank near its air intake end and terminating near its other end close to the surface of the liquid having slidably engagement with the tank sides so as to form a restricted leaving passage for the air, and means independent of the first mentioned means to adjust the position of the baffle relative to the fuel level.

8. A carburetor comprising a liquid fuel tank, means to maintain a constant level of fuel in the tank, a member angularly disposed above the liquid fuel and defining with the walls of the tank and the surface of the fuel a passage of gradually decreasing area, means for passing a current of air through said passage in the direction of its decreasing area and outwardly between one edge of said member and the surface of the liquid, and means to vary the angular relation of the member with respect to the liquid fuel surface.

In testimony whereof I affix my signature,
RUBIN MILLARD SWEARENGIN.
